(57) **CLAIM**

The ornamental design for a hood for an automobile, as shown and described.

DESCRIPTION

FIG. 1 is a front elevational view of a hood for an automobile in accordance with our new design; FIG. 2 is a top plan view thereof;

FIG. 3 is a cross sectional view thereof, taken in the direction of line 3-3' of FIG. 2;

FIG. 4 is a cross sectional view thereof, taken in the direction of line 4-4' of FIG. 2;

FIG. 5 is a cross sectional view thereof, taken in the direction of line 5-5' of FIG. 2;

FIG. 6 is a cross sectional view thereof, taken in the direction of line 6-6' of FIG. 2;

FIG. 7 is a bottom plan view thereof;

FIG. 8 is a right side elevational view thereof;

FIG. 9 is a left side elevational view thereof;

FIG. 10 is a top, front and right side perspective view thereof; and,

FIG. 11 is a rear elevational view thereof.

The bottom view and bottom surfaces of the hood form no part of the claimed design since the bottom view and bottom surfaces are hidden when the hood is mounted to an automobile.
